United States Patent Office

Des. 183,159
Patented July 8, 1958

183,159

STAIRWAY HAND RAILING UNIT

Louis Blum, Pittsburgh, Pa., assignor to Blumcraft of Pittsburgh, Pittsburgh, Pa., a firm

Application February 8, 1956, Serial No. 40,078

Term of patent 14 years

(Cl. D13—7)

Figure 1 is a perspective view of a stairway hand railing unit showing my new design; and,

The broken lines are shown for illustrative purposes only.

I claim:

The ornamental design for a stairway hand railing unit, as shown and described.
